DESIGN FOR A CLIP FOR WEARING APPAREL OR SIMILAR ARTICLE

John F. Pivcevich, New York, N. Y.

Application June 26, 1944, Serial No. 114,204

Term of patent 7 years

(Cl. D17—3)

To all whom it may concern:

Be it known that I, John F. Pivcevich, a citizen of Yugoslavia, residing at New York city, county of New York, and State of New York, have invented a new, original, and ornamental Design for a Clip for Wearing Apparel or Similar Article, of which the following is a specification, reference being had to the accompanying drawing, forming a part thereof wherein:

for wearing apparel or similar article showing my new design; and

Figures 2, 3, and 4 are, respectively, a side elevation, a rear elevation, and a top plan view of the same.

I claim:

The ornamental design for a clip for wearing apparel or similar article, as shown.

JOHN F. PIVCEVICH.
